APPARATUS FOR MAKING SOAPSUDS

Filed Feb. 14, 1931

INVENTOR.

Philip C. Doyle

BY

Fay Oberlin & Fay
ATTORNEY-S.

UNITED STATES PATENT OFFICE

PHILIP C. DOYLE, OF CLEVELAND, OHIO, ASSIGNOR TO THE STANDARD OIL COMPANY, OF CLEVELAND, OHIO, A CORPORATION OF OHIO

APPARATUS FOR MAKING SOAPSUDS

Application filed February 14, 1931. Serial No. 515,754.

The present invention relates to dissolving apparatus, and more particularly apparatus for preparing solutions such as of soap, etc.; and it is among the objects of the invention 5 to provide apparatus conveniently attachable to a water connection, and being efficient in control of a solution of desired strength, without undue tendency to carry through undissolved particles. Other objects and advantages will appear as the description proceeds.

To the accomplishment of the foregoing and related ends, said invention, then, comprises the features herein after fully described, and particularly pointed out in the 15 claims, the following description and the annexed drawing setting forth in detail certain structure illustrative of the invention, this being indicative, however, of but one of the 20 various ways in which the principle of the invention may be employed.

In said annexed drawing:

Fig. 1 is a side elevational view showing an embodiment of the invention; and Fig. 2 25 is a vertical sectional view on enlarged scale.

Referring more particularly to the drawing, there is shown a container 2, whose form and dimensions may vary, but which conveniently may be of a size adaptable to attachment to a water spigot 3, a suitable connector 4 being provided. A charging opening 5 is arranged at the upper portion of the container, and a water inlet connection 6. Desirably, the latter may be arranged with a baffle or 30 partial partition 7 therebeneath, such assisting in preventing too extensive currents in the reservoir portion of the container. Extending into the container further down, and preferably well toward the lower end, is a further water inlet pipe 8, preferably having its own valve-control 9. A partition 10 is arranged above the inlet 8, and such partition is provided with perforations 11, at 35 least at its lower portion, the partition preferably being positioned on a slant.

A further mixing and straining partition 12 may be arranged beneath the liquid-inlet 8, and this partition also has perforations 40 13. At the lower end of the container, a dis-

charge 14 is arranged, such as for convenient discharge into any desired receptacle 15.

In use, the material to be dissolved, for instance, a soft soap or flake soap, is charged in through the opening 5, and the dissolving liquid, or water, is supplied from the spigot 3, the flow being regulated to the desired rate consistent with the strength of solution or suds wanted. By proper control of the lower inlet 8 by its valve 9, the strength may be 55 gradated as may be desired. Mixing and dissolving occurs in the upper compartment above partition 10, and the solution proceeds through the perforations 11 to the lower chamber, where a further mixing with incoming liquid occurs, the resultant solution then passing through perforations 13 and discharging through outlet 14, for instance into a barrel 15 as commonly employed in automobile-washing establishments. The strength 60 of solution may be regulated closely by a proper set of the valve 9, and the spigot may be opened and closed as a main-control.

Other modes of applying the principle of the invention may be employed, change being 65 made as regards the details described, provided the means stated in any of the following claims, or the equivalent of such, be employed.

I therefore particularly point out and distinctly claim as my invention:

1. Apparatus of the character described, comprising a container having a charging opening and a liquid-inlet in its upper portion, a partition in said container beneath 75 said liquid-inlet having perforations, a valve-controlled liquid-inlet beneath said partition, a perforated partition beneath said last-named inlet, and a discharge outlet independent of said last-named inlet in the lower portion of the container.

2. Apparatus of the character described, comprising a container having a charging opening and a liquid-inlet in its upper portion, a partial partition extending horizontally in the upper portion of said container beneath said liquid inlet, a perforated partition in said container beneath said partial partition, a valve-controlled liquid-inlet beneath 85 said partition, another perforated par-

tion beneath said last-named liquid-inlet, and a discharge outlet in the lower portion of the container.

3. Apparatus of the character described, comprising a container having a charging opening and a liquid-inlet in its upper portion, a partial partition extending horizontally in the upper portion of said container beneath said liquid-inlet, a sloping partition therebeneath having perforations in its lower portion, a controllable liquid-inlet beneath said last-named partition, a perforated reversely-sloping partition beneath said last-named liquid-inlet, and a discharge outlet in the lower portion of the container.

15 Signed by me this 6th day of February, 1931.

PHILIP C. DOYLE.
